UNITED STATES PATENT OFFICE

2,586,277

HORSE SIMULATED SWING

Cecil J. Voelker, Yakima, Wash.

Application May 10, 1949, Serial No. 92,427

1 Claim. (Cl. 155—65)

1

This invention relates to amusement devices, and more particularly to an amusement device in the form of a swing with the seat portion thereof constructed to simulate a horse.

An important object of the invention is to provide a swing of this character wherein the seat portion or horse of the swing will be operated by pressure exerted on pivoted treadles on which the feet of the person occupying the seat, rest.

Another important object of the invention is to provide means for supporting the swing in such a way as to eliminate side sway during the swinging of the device.

With the foregoing and other objects in view which will appear as the description proceeds, the invention consists of certain novel details of construction and combinations of parts, hereinafter more fully described and pointed out in the claim, it being understood that changes may be made in the construction and arrangement of parts without departing from the spirit of the invention as claimed:

Referring to the drawings:

Figure 1 is a front elevational view of a swing constructed in accordance with the invention.

Fig. 2 is a sectional view taken on line 2—2 of Fig. 1.

Fig. 3 is an enlarged perspective view illustrating the treadle construction of the swing.

Referring to the drawings in detail, the swing comprises an inverted U-shaped frame 5 constructed preferably of pipe material, with its ends embedded in concrete bases 6.

The swing proper is supported by the cross pipe 7 to which the arm 8 is secured at a point intermediate the ends of the cross pipe 7, the arm being wide at its point of contact with the pipe 7, where it is provided with openings through which the bolts 9 pass, the bolts 9 also passing through openings formed in the yoke 10 and cross pipe 7, as clearly shown by Fig. 2 of the drawings, thereby firmly securing the arm 8 in place. This arm 8 extends forwardly an appreciable distance, where it is provided with an opening, in which the hook 11 is mounted, the hook passing into the ring 12 of the sheave 13.

Extending downwardly from the yoke 10 are spaced arms 14 which are formed with openings that accommodate the bolt 15 that provides a pivot for the member 16, the bolt being shown as passing through an opening formed in the upper end of the swing supporting pipe 17. Spacers 18 are mounted on the bolt 15 between the pipe 17 and spaced arms 14, holding the pipe 17 against movement longitudinally of the bolt.

2

Connected with the lower end of the swing supporting pipe 17, are the bars 19 which extend downwardly and are connected to the treadles 20 by means of the rod 21, which is secured to the

treadles, as shown by Fig. 3 of the drawings.

The outer ends of the treadles are connected by the bar 22 and to this bar 22 the cable 23 is connected, the cable 23 operating over the sheath 13 whence it passes through an opening in the

10 pipe 17 at a point adjacent to the upper end thereof.

Secured between the bars 19, is the wooden horse 24, provided with a seat 25 secured to the back thereof, simulating a saddle.

15 Mounted on the treadles 20 are foot pieces 26, which are formed with openings in which the bolts 27 are positioned, the bolts 27 being disposed within the elongated openings 28 so that the foot pieces 26 may be adjusted longitudinally 20 of the elongated openings 28, whereby the foot pieces may be adjusted for use by children of various sizes.

A chain indicated by the reference character 29, connects the horse 24 with the treadles 20 to 25 restrict movement of the treadles away from the horse and thereby restrict swinging movement of the swing supporting pipe 17.

The reference character 30 indicates reins, which are connected with the head section of the 30 horse to be gripped by the person operating the swing, to balance himself.

In operation, a person seated on the seat 25 may, by pressing downwardly on the treadles 20, cause a pull on the upper end of the pipe 17, by 35 the cable 23, moving the swing supporting pipe 17 and horse supported thereon forwardly. When pressure is released the lower end of the swing supporting pipe with the horse mounted thereon, will swing rearwardly and the action of 40 the swing will simulate the movements of a pendulum.

Having thus described the invention, what is claimed is:

In a swing, a supporting frame including a 45 horizontal cross pipe, a vertical swing supporting pipe, means for pivotally connecting the vertical swing supporting pipe to the horizontal cross pipe, a seat member, means for securing the seat member to the vertical swing supporting pipe, 50 treadles forming a part of the swing, means for connecting the treadles to the lower end of the vertical swing supporting pipe, said treadles having elongated openings disposed longitudinally thereof, foot pieces mounted on the treadles and 55 extending laterally therefrom, bolts extending

from the foot pieces and being movable in the elongated openings, adjusting the foot pieces longitudinally of the treadles, a cable secured to the free ends of the treadles, the opposite end of said cable being connected to the swing supporting pipe, and a sheave mounted at the upper end of the supporting frame over which the intermediate portion of the cable operates, whereby pressure on the treadles moves the swing supporting pipe and swing seat with a swinging motion. 10
